US00D831060S

(12) **United States Design Patent** (10) **Patent No.:** **US D831,060 S**
Bachman et al. (45) **Date of Patent:** **** Oct. 16, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **William Martin Bachman**, San Jose, CA (US); **Taylor Gerard Carrigan**, San Francisco, CA (US); **Alexander C. D. Fringes**, San Francisco, CA (US); **Monika E. Gromek**, Oakland, CA (US); **Ofer Morag**, Oakland, CA (US); **Jeffrey L. Robbin**, Los Altos, CA (US)

(73) Assignee: **Apple Inc.**, Cupertino, CA (US)

(**) Term: **15 Years**

(21) Appl. No.: **29/615,638**

(22) Filed: **Aug. 30, 2017**

Related U.S. Application Data

(63) Continuation of application No. 29/570,462, filed on Jul. 8, 2016, now Pat. No. Des. 797,782, which is a continuation of application No. 29/523,739, filed on Apr. 13, 2015, now Pat. No. Des. 765,118.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design. The dashed broken lines inside of the peripheral dashed broken lines illustrate portions of the graphical user interface and form no part of the claimed design.
